UNITED STATES PATENT OFFICE.

ALBERT ROBERT, OF TRENTHAM, STOKE-UPON-TRENT, ENGLAND, ASSIGNOR TO THE
MORGAN BELLEEK CHINA COMPANY, OF CANTON, OHIO, A CORPORATION.

DESIGN FOR A PLATE OR SIMILAR ARTICLE.

Application filed November 25, 1927. Serial No. 24,270. Term of patent 14 years.

To all whom it may concern:

Be it known that I, ALBERT ROBERT, a subject of the King of England, residing at Trentham, Stoke-upon-Trent, England, have invented a new, original, and ornamental Design for a Plate or Similar Article, of which the following is a specification, reference being had to the accompanying drawing, forming a part hereof.

The figure is a top plan view of a plate showing my new design, it being understood that the ornamentation shown between the two dot and dash lines is continued throughout.

What I claim is:

The ornamental design for a plate or similar article, as shown and described.

ALBERT ROBERT.
